P. T. C. DUMAIS

FASTENER

Filed Sept. 18, 1922

INVENTOR
PAUL T. C. DUMAIS.

BY *Fastener Company*
ATTY.

UNITED STATES PATENT OFFICE.

PAUL THOMAS CONCORD DUMAIS, OF HULL, QUEBEC, CANADA.

FASTENER.

Application filed September 18, 1922. Serial No. 588,987.

To all whom it may concern:

Be it known that I, PAUL THOMAS CONCORD DUMAIS, a subject of the King of Great Britain, and a resident of the city of Hull, in the Province of Quebec and Dominion of Canada, have invented certain new and useful Improvements in Fasteners, of which the following is a specification.

This invention relates to improvements in fasteners, or locking device for packages of merchandise and the like, and the objects of the invention are to provide flexible means of this kind that can be locked on itself to seal railroad cars, and similarly locked to secure packages of merchandise.

Further objects are to provide a simple economically constructed and effective fastening device of this character that can be readily manufactured and marketed in large quantities.

With the foregoing and other objects in view, the invention consists essentially in the improved construction hereinafter described in detail in the specification and illustrated by the drawings that form part of the same.

Referring to the drawings, in which like characters of reference indicate corresponding parts in each figure, and in which:

Figure 1 is a plan view of the fastener in open position adapted for securing packages of merchandise and the like.

Figure 2 is a plan view of the invention adapted for packages with tag attached, in open position.

Figure 3 is a detailed view of the baggage fastener in folded position, showing the tag string wound therearound.

In the drawings:
A represents the fastener adapted for use with packages of merchandise and designed to be folded on itself and to lock over the cord or string having a tag attached thereto at one end, and the other end engaging with the body of the fastener as shown in Figure 2. The fastener A comprises a strip of flexible metal 10 having formed integral therewith at each end the male and female locking members 11 and 12, and provided intermediate of said members in the strip portion with a tongued member 14, adapted, as above mentioned and as shown in Figure 2, to engage with the cord or string of a baggage tag.

The male member 11 is formed with a head or conical top spaced from the base

and designed to engage with a spring 15 wound within the cylindrical body of the member 12 whereby on the member 11 being so engaged with the member 12, the fastener is locked and cannot be removed without breaking the fastening members.

For packages for postal bags and the like, the fastener is provided with the tongue 14 with which is engaged the end of a tag 65 string, the string being then wound around, as shown in Figure 3, the body portion of the fastener, which in turn is folded on itself so as to engage the member 11 with the member 12, and thereby locking the string 70 thereon, which has already been folded therearound.

From the foregoing, it will be seen that I have invented a very simple and effective locking fastener, particularly adapted for the purposes for which it is designed, namely, the securing of packages of merchandise, mail bags, and baggage generally.

As many changes could be made in the above construction and many apparently widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

1. A device of the character described comprising a metal strip having the ends 90 formed to provide locking members and provided intermediately of said locking ends with a cut out tongued member.

2. A device of the character described comprising a strip of flexible metal formed 95 at each end with button-shaped engaging members designed on the strip being folded on itself to lock the ends together, a tongued member formed in the strip between said end locking members.

3. A device of the class described comprising a strip of flexible metal intermediately cut to form a tongue adapted to engage with a string or the like, the ends of said strip being designed to form, respectively, a conical-headed engaging member and a spring-actuated receiving member whereby on the strip being folded said ends are locked.

4. A flexible metal strip having its ends 110 formed to provide an engaging member at one end and a receiving member at the other

end, a tongue formed in the strip body, said tongue being adapted to engage with a string or the like designed to be folded around the body of the strip and to be secured thereon by folding the strip on itself whereby the strip is locked by the end engaging members.

5. A device of the character described comprising a flexible metal strip formed 10 with a tongue therein adapted to engage with tag securing means, said strip having

formed at the ends and integral therewith an engaging member with a conical-shaped head spaced from the base and a receiving member with an aperture therein surrounded by a cylindrical spring, respectively, said members being designed on the strip being folded on itself to engage with one another to lock the strip. 15

In witness whereof I have hereunto set 20 my hand.

PAUL THOMAS CONCORD DUMAIS.
